(57) **CLAIM**

The ornamental design for an electrode assembly for transdermal stimulation, substantially as shown and described.

DESCRIPTION

FIG. 1 is a top view of an electrode assembly for transdermal stimulation in accordance with the present invention.

FIG. 2 is a bottom view of the electrode assembly for transdermal stimulation of FIG. 1.

FIG. 3 is a first side view of the electrode assembly for transdermal stimulation of FIG. 1; and,

FIG. 4 is a second side view of the electrode assembly for transdermal stimulation of FIG. 1.

The broken lines immediately adjacent to the shaded areas represent the bounds of the claimed design, all other broken lines represent environmental subject matter that form no part of the claimed design.

1 Claim, 3 Drawing Sheets

FIG. 1

FIG. 2

FIG. 3

FIG. 4
